UNITED STATES PATENT OFFICE.

DANIEL FENSKA, OF MILWAUKEE, WISCONSIN, ASSIGNOR OF ONE-HALF TO JOHN C. KLEIST, OF MILWAUKEE, WISCONSIN.

FLYING-MACHINE.

1,378,100.

Specification of Letters Patent. Patented May 17, 1921.

Application filed December 15, 1919. Serial No. 344,848.

To all whom it may concern:

Be it known that I, DANIEL FENSKA, a citizen of Canada, residing at Milwaukee, in the county of Milwaukee and State of Wisconsin, have invented certain new and useful Improvements in Flying-Machines, of which the following is a specification.

This invention relates to improvements in flying machines and more particularly to 10 helicopters. One object is to provide a machine of this type that is simple in construction, efficient and safe in operation and relatively cheap to manufacture. A further object is to provide a machine of this type 15 in which the lifting and supporting wings or propellers are adjustable to graduate the speed of an ascent or descent and to determine the direction thereof, that is, whether perpendicular or oblique.

With the foregoing and other objects in view the invention consists in the combination and arrangement of parts to be herein-after fully described, pointed out in the appended claim and illustrated in the accompanying drawings which form a part of this 25 specification and in which—

Figure 1 is a view of my improved flying machine in side elevation.

Fig. 2 is a section taken on line 2—2 of 30 Fig. 1.

Fig. 3 is a vertical sectional view at right angles to Fig. 1.

Figs. 4 and 5 are enlarged fragmentary sectional views illustrating the wing tilting 35 mechanism, said views being disposed at right angles, one to the other.

Like reference characters denote corresponding parts throughout the several views.

40 The reference numeral 1 denotes the basket of the machine arranged upon legs 2 which are provided with the shock absorbers 3 to assimilate the impact when a landing is made. The basket is provided, further, with the rudder 4 controlled by the hand lever 5, and with the motor 6. The motor shaft 7 is connected by bevel gears 8 with the rotary sectional shaft 9, 10, the sections of which are connected by the universal joint 11. The shaft section 9 has its

angle with the floor of the basket fixed while the shaft section 10 is adjustable with relation to the section 9 by means of the sleeve support 12, in which said shaft section rotates, and link 13 which connects said sleeve support to the screw shaft 14, journaled in supports 15 carried by the basket, said screw shaft being operable by its handle 16.

For a perpendicular ascent or descent the shaft sections 9, 10 are retained in alinement 60 by means of the screw shaft 14 and connections. For an oblique ascent or descent the shaft section 10 is disposed out of alinement with the section 9. This operation is performed by rotation of the screw shaft 65 handle 16. The speed of the ascent or descent is controlled in the following manner: The sleeve support 12 is formed along one face with the teeth 17 over which the pawl 70 of the hand lever 18 works, said hand lever being fulcrumed to the sleeve support and connected by pitmen 19, 20 to the rotary block 21 that is keyed to and rotates with the shaft section 10, the said pitmen 19, 20 being so secured to the block 21 as to permit its 75 rotation.

To the block 21 the oppositely disposed wing shafts 22, 23 are secured which rotate with the block and carry the wings 24, 25. The block 21 is slidably keyed to the shaft section 10, the shaft ends 26 being diminished and disposed in the curved shaft 80 grooves 27 so that an adjustment of the block will operate to dispose the wings 24, 25 horizontally or at an angle to the horizon. In 85 the horizontal position the machine will be caused to rise or descend slowly while in a position at an angle to the horizon the ascent or descent will be more rapid, the greater the angle the greater the speed.

What is claimed is:—

In a flying machine, a basket, a motor driven sectional shaft carried by said basket, a sleeve support, one shaft section rotating in said sleeve, teeth formed along one face 95 of said sleeve support, a hand lever fulcrumed to said sleeve support and formed with a pawl in engagement with the teeth of said sleeve support, a block slidably keyed to the last named shaft section and rotating 100

therewith, pitmen connecting said block and hand lever, and shafted wings carried by said block and adjustable relatively thereto through movement of said block relative to its shaft section.

In testimony that I claim the foregoing as my own I have hereto affixed my signa-

ture in the presence of two subscribing witnesses.

DANIEL FENSKE.
